UNITED STATES PATENT OFFICE.

MICHAEL SCHWARTZ, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TRAFFIC RECORDER FOR TELEPHONE SYSTEMS.

Application filed July 12, 1922, Serial No. 574,494. Renewed August 4, 1928.

The present invention relates in general to traffic recorders for telephone systems. More specifically, the invention is concerned with devices which record the traffic on trunks 5 extending between automatic switches.

An object of the invention is to provide a recording device for registering the number of times a trunk line is seized and then released within a very short interval, together with means for registering the number of times the trunk line is used for a longer interval as for a successful call to a called line.

Another object of the invention is to provide a device for registering the total length of time the trunk line is in use.

Another object of the invention is to register the number of times all the trunks in a group become busy, and also to record the 20 total length of time that this all trunk busy period lasts.

Still another object of the invention is to provide means for at all times showing the 25 number of simultaneous connections over the group of trunks under observation.

A further object of the invention is to provide an improved timing device, whereby the recording mechanism may be controlled at various speeds.

30 There are other objects of the invention which have not been mentioned, but which, together with those enumerated above, will be described hereinafter, reference being had to the accompanying drawings.

35 Referring now to the drawings, comprising Figs. 1 and 2, there is shown sufficient apparatus involving the invention to enable the same to be readily described and understood.

40 Referring now more particularly to Fig. 1, in the upper portion of the drawing, designated by the reference character E, is an automatic selector switch of the usual Strowger type, the construction and circuits of which are well understood.

45 At A is indicated a recording milli-ammeter for registering the total number of simultaneous calls in the group of trunks under observation. This milli-ammeter may be of any well-known or desired type.

50 The traffic recording device proper consists of the equipment designated by the reference characters M and M'. The equipment shown at M consists merely of a group

of meters 100, 101, and 102, which record 55 the required data. The equipment shown at M' consists of two meters 88 and 89, a group of relays, and a simple rotary minor switch S'. This equipment controls the operation of the meters 100, 101, and 102 60 and also the meters 88 and 89.

The equipment shown at M may be used alone without the equipment M', if it is desired to merely register the total number of calls over a trunk line, and the total length 65 of time the trunk is held in use. In the present instance, it will be assumed that it is desired to record the traffic on a group of ten trunks. In this case, each trunk line will have individual to it apparatus such as 70 M and M'. Thus, the equipment M and M' is individual to the trunk line comprising conductors 10-12, inclusive, with the exception of the meters 89 and 102. The meter 89 is common to the ten trunk lines of the 75 group and serves to register when all trunks become busy. The meter 102 is likewise common to the ten trunk lines and registers cumulatively the total length of time all ten trunks are in use.

80 The recording apparatus including the equipment M and M' may be used to record the traffic on a trunk line extending from a line switch to a first selector, a selector trunk line, or in fact, any kind of trunk 85 over which it is desired to record the traffic.

In Fig. 2, there is shown the timing mechanism. This is common to all the traffic recording devices of the exchange, and comprises essentially a constantly operating 90 timing device P and two rotary switches C and S. The rotary switch S is of very simple construction and comprises wipers 180 and 181, an operating magnet 168 and a release magnet 169. The rotary switch C, 95 whose wipers move in a forward direction only, is of the same general mechanical construction as the well-known rotary line switches.

Having briefly described the apparatus 100 shown in the drawings, a detailed description of its operation will now be given. For this purpose, it will be assumed that the trunk line comprising the conductors 10-12, inclusive, is seized by another selector switch 105 or by a line switch under the control of a calling subscriber. Immediately upon the subscriber's line being extended to the line

relay 15 of the selector E, this relay is energized. Upon operating, relay 15, at armature 20, closes the circuit of the slow acting relay 16. The latter relay, upon energizing, at armature 21 prepares the operating circuits of the selector E, and at armature 22 places ground upon the release trunk conductor 11, thereby establishing a holding circuit for the preceding switch or switches.

The calling subscriber may now operate his calling device in accordance with the next digit in the desired number. By this operation a series of interruptions is produced in the circuit of the line relay 15 of the selector E, which deenergizes a plurality of times in response thereto. At each retraction of the armature 20 of the line relay 15, an impulse of current is sent to the vertical magnet 46 in series with the slow acting relay 17. The vertical magnet 46 operates to raise the shaft of the switch carrying the wipers 35-37, inclusive, step by step until the said wipers are brought opposite the proper level of bank contacts. The slow acting relay 17 is energized in series with the vertical magnet, and maintains its armature attracted throughout the vertical movement of the switch. Upon the first vertical step of the switch shaft, the relay 17 being now energized, a circuit is completed for the stepping relay 18. Upon operating, relay 18 establishes a locking circuit for itself at its upper armature, and at its lower armature prepares a circuit for the rotary magnet 44. Shortly after the end of the vertical movement, the slow acting relay 17 deenergizes to close the circuit of the rotary magnet 44. The magnet 44 operates to advance the switch wipers into engagement with the first set of bank contacts in the selected level, and also opens the locking circuit of the stepping relay which deenergizes, opening the circuit of the rotary magnet which deenergizes also. If the trunk line with which the switch wipers are now in engagement is busy, the stepping relay 18 will again be energized from ground upon the test contact of the associated trunk line. Relay 18, upon operating, completes a locking circuit for itself and also closes the rotary magnet circuit. The rotary magnet operates to advance the wipers of the switch into engagement with the next set of bank contacts and opens the circuit of the stepping relay. The stepping relay deenergizes to open the circuit of the rotary magnet, which also deenergizes. The alternate operation of the relay 18 and the rotary magnet 44 continues until the wipers of the selector E are rotated into engagement with a set of bank contacts associated with an idle trunk line, which, we will assume, are the bank contacts 38-40, inclusive. When the wipers 35-37, inclusive, are brought into engagement with this set of bank contacts, the

rotary movement of the selector E ceases, and the switching relay 19, which during the preceding operations of the switch has been short circuited, is energized in series with the stepping relay 18. Relay 19 operates to extend the calling line over the wipers 35 and 37, bank contacts 38 and 40, trunk conductors 41 and 43, to the windings of the line relay of the seized switch.

The line relay of the selected switch immediately energizes to close the circuit of its associated slow acting release relay. The latter relay operates to prepare the circuits of the seized switch for operation, and to place ground upon the release trunk 42 to establish a holding circuit for the selector E and the preceding switch or switches.

The further extension of the connection in response to the remaining digits dialled by the calling subscriber will take place in the usual manner, and as this extension does not concern the present invention, it will be not described herein.

It will be noted that as soon as the selector E is seized, ground is placed upon the release trunk conductor 11, and a circuit is completed extending from this ground over conductor 13, terminal 50 of the recording device M, through the resistance 60, and through the recording milli-ammeter A to battery. The current flowing through the resistance 60 and the winding of the milli-ammeter affects the marking pen in the usual manner, causing the line on the chart to be raised a suitable distance to indicate another call. All the release trunks of the group of trunks are connected through a resistance similar to 60 to the recording milli-ammeter so that the reading of the milli-ammeter is always proportionate to the number of simultaneous calls in the group. The resistances, such as 60, are sufficiently high so that there is no interference by a ground potential being extended through these resistances to the other release conductors of the trunks of the group when one or more become busy. There is also another circuit completed by the grounding of conductor 11, which extends from terminal 50 by way of terminal 51, working contact of spring 62 of key K and the said spring, this key being in operated position when it is desired to record the traffic on the associated trunk, terminal 52, terminal 55, through the winding of the high resistance relay 70, through the winding of the low resistance relay 71, terminals 56 and 53, and through the winding of the meter magnet 100 to battery. Only the high resistance relay 70 is operated over the above circuit. Upon attracting its armatures, relay 70, at armature 76, closes a circuit which extends from ground by way of the front contact of armature 76 and the said armature, terminals 57 and 54, working contact of spring 61 and the said

spring, through the winding of the meter magnet 101, conductor 112, to terminal 163 of the timing device. The terminal 163 of the timing device is being connected to battery once every second by the operation of the timing mechanism, as will be described, and consequently, the meter magnet 101 is operated to register every second, thus indicating by its cumulative registration for 10 various calls the total length of time that the trunk is held in use. Further results of the energization of relay 70 are that at armature 77 a circuit is prepared for the release magnet 74 of the minor switch S', at 15 armature 78 a point is closed in a certain chain circuit, which will be described, and at armature 79 the rotary magnet 73 of the rotary switch S' is connected over conductor 110 to the terminal 164 of the timing device. 20 The terminal 164 of the timing device is being momentarily connected to battery once every half second, as will appear later, and consequently, the motor magnet 73 operates to advance the wiper 95 one step 25 every half second. At the end of four seconds, the wiper 95 is advanced into engagement with the bank contact 96, whereupon the winding of the relay 70 is short circuited. By this operation relay 71 and the meter magnet 100 are energized. Upon operating, 30 relay 71, at armature 80, establishes a locking circuit for itself exclusive of the wiper 95, at armature 81 closes a new circuit for the meter 101, at this same armature closes 35 the circuit of the slow acting relay 93, at armature 82 closes a circuit for the release magnet 74 of the minor switch S', at armature 84 closes a new point in the chain relay above mentioned to provide against the de- 40 energization of relay 70, and at armature 85 transfers the circuit of the motor magnet 73 of the minor switch S' from connection with the terminal 164, into connection with the terminal 165 of the timing device. As 45 the winding of relay 70 has been short circuited by the operation of wiper 95 of the switch S', this relay will deenergize. However, due to the fact that it is short circuited, it will be made slow acting and maintain 50 its armature attracted for a short interval after the short circuiting of its winding, long enough to allow the minor switch S' to be released. The operation of the meter 100 serves to register one call. The slow acting 55 relay 93, upon operating, at armature 87 opens a point in the circuit of relay 72, and at the front contact of this armature prepares a circuit for the release magnet 74. As the motor magnet 73 of the minor switch S' is now connected to the terminal 165 of the timing device, it will be operated once 60 every 50 seconds. Each time the magnet 73 operates it advances the wiper 95 one step. At the end of 500 seconds, the wiper 95 will 65 engage the bank contact 97, whereupon, if

the connection is not terminated, the lamp L will be lit. The operation of the lamp L serves to notify the attendant at the exchange that the particular trunk having the equipment M has been in use for a prolonged period of time. The attendant may now examine this trunk to see if it is held due to some unnatural condition. 70

It will be remembered that the relay 71, upon operating, closes a point in a certain chain circuit. This circuit includes contacts on other relays, such as relays 70 and 71, in other equipment such as M' which are associated with the other trunks of the group. When all the trunks of the group 80 become busy, the chain is closed, and the meter magnet 89 will be operated to indicate this fact. 75

It will be noted that each time the timing meter magnet 101 operates, the armature 106 is caused to engage its working contact. This armature and contact is included in another chain circuit which has contacts on various other magnets, such as 101 in the groups of ten trunks with which these meters 90 are associated. When all the trunks of this group of ten become busy, the meter magnet 102 will be operated to denote by its cumulative operation the time that these trunks are held in use. 95

Should it happen that, when the trunk line comprising conductors 10-12, inclusive, is first seized, the subscriber should replace his receiver before the wiper 95 advanced into engagement with the bank contact 96, the meter magnet 100 would not be operated. However, when the connection is released, the relay 70 will be deenergized, while the minor switch S' will be off normal. The slow acting relay 72 is accordingly energized 100 in series with the release magnet 74, and operates at its armature 86 to close the circuit of the meter 88. Meter 88 operates once to register that the trunk line has only been used for a short period of time, less than 105 four seconds, while magnet 74 operates to restore the minor switch S' to normal. 110

When the connection is released, ground is removed from the test contact 39 with which the test wiper 36 of the selector E 115 is in engagement, and the selector E is released in the usual manner. When ground is removed from the release trunk conductor 11, the relay 71 in the metering equipment M' is deenergized. By the deenergization 120 of relay 71, the circuit of the slow acting relay 93 is opened. After the deenergization of relay 71 and before the deenergization of relay 93, a circuit is completed for the release magnet 74 over a path extending 125 from ground by way of front contact and armature 87, armature 83 and its back contact, back contact and armature 77, off normal spring 75 and its working contact, and through the winding of the release magnet 130

74 to battery. Accordingly, the minor switch S' is released. Another result of the deenergization of relay 71 is that the circuit of the timing meter 101 is opened at armature 81. The operation of the other contacts on the relay 71 serve merely to restore certain circuits to normal.

Having described the operation of the metering device when the equipment M' is used, its operation when only the equipment M is used will now be described. In this case, all the terminals 50-54, inclusive, will be connected together. Now, when ground is placed upon the release trunk conductor 11 at the time the trunk is seized, the meter magnet 100 is immediately operated to register one connection, and the timing meter 101 immediately starts to operate. The current flowing through the resistance 60, of course, causes the milli-ammeter A to register another connection. When the connection is released the selector E is restored to normal and the equipment M ceases functioning.

The operation of the timing device shown in Fig. 2 will now be described. The device P consists of a constantly operating pendulum 150, which is controlled by the relay 151. Its operation is as follows: When the pendulum swings to the left, it closes the springs 150 and 156, whereupon a circuit is completed for the relay 151. Upon energizing, relay 151 attracts its armature 155. As the tension is taken off spring 156, this spring operates and causes the pendulum spring 150 to be forced to the left, thereby moving the pendulum to the right. When the pendulum swings to the right, it opens the circuit of the relay 151, which deenergizes, causing the spring 156 to assume its normal position. The same operation is then repeated. An additional result of the energization of the relay 151 is that at armature 152 battery is connected to the conductor 157, which extends through the stepping magnet 167 of the rotary switch C to ground. The weight on the pendulum 150 is so adjusted that the relay 151 is energized once every half second. The terminal 164 of the timing device thus has battery placed upon it once every half second. The stepping magnet 167 is operated once every half second and serves to advance the switch wipers 175-178, inclusive, one step every half second. In the contact banks adapted to be engaged by wipers 175 and 176, the contacts are tied together alternately. In the bank adapted to be engaged by wiper 175, the first, third, and other odd contacts are connected together and to the terminal 163. In the contact bank adapted to be engaged by wiper 176, the second, fourth, and other even contacts are connected to the terminal 163. The wipers 175 and 176 are set opposite each other so that when the wiper 175 engages the first bank contact, the wiper 176 leaves the

twenty-fifth bank contact. By this arrangement the conductor leading to the terminal 163 is connected to battery once every two steps of the wipers 175 and 176. In the contact bank adapted to be engaged by wiper 177, every fifth contact is connected together and thence to the terminal 162. Thus, the terminal 162 is connected to battery once every two and one-half seconds. Only one contact in the bank adapted to be engaged by wiper 178 is connected to the terminal 160. Another contact is connected to the terminal 161. Thus, the terminals 160 and 161 are connected to battery once every twenty-five seconds, that is, each fifty steps of the wiper 178. The space between the battery impulses at the terminals 160 and 161 is determined by the space between the bank contacts to which these terminals are connected in the bank adapted to be engaged by wiper 178. In addition, the wiper 178 in engaging its twenty-fifth bank contact, closes the circuit of the stepping magnet 168 of the minor switch S. Magnet 168 operates to advance the wipers 180 and 181 one step every twenty-five seconds. As alternate contacts in the bank of wiper 180 are connected together and to the terminal 165, this terminal is connected to battery once every fifty seconds. When the wipers 180 and 181 reach their tenth position, the next time the wiper 178 engages its twentieth bank contact, the slow acting relay 170 is energized. Relay 170 operates to close the circuit of the release magnet 169. Magnet 169 operates to restore the minor switch S to normal, whereupon the same operation is repeated. In this manner battery is connected to the terminal 164 every one-half second, to the terminal 163 every second, to the terminal 162 every two and one-half seconds, to the terminals 160 and 161 every twenty-five seconds, and to the terminal 165 every fifty seconds, whereby the traffic recording devices are controlled as has been described. Terminals 160, 161 and 162 are provided to make it possible to change the rate of operation of time controlled mechanisms of the recording equipment. These terminals may also be utilized in operating other apparatus at the exchange requiring a different rate of operation than could be obtained by connecting with any of the terminals 163, 164, or 165.

What I claim is:

1. In a telephone system, a trunk line, means for making said trunk line busy, a metering device, and means responsive to the busy condition of said trunk line for operating said device only if said trunk line is held in use a predetermined period.
2. In a telephone system, a trunk line, means for making said trunk line busy, a metering device, means responsive to the busy condition of said trunk line for operating said device if said trunk line is held in use

a predetermined period, and means for preventing the operation of said device if said trunk is held in use for a lesser period of time.

5 3. In a telephone system, a trunk line, means for making said trunk line busy, two registering devices, and means responsive to the busy condition of said trunk line for operating one device if said trunk line is held 10 a predetermined time and for operating the other device if said trunk line is held less than said predetermined time.

4. In a telephone system, a trunk line, means for making said trunk line busy, an 15 automatic switch associated with said trunk line, an operating magnet for said switch, a circuit for said magnet, a meter, means responsive to the busy condition of said trunk line for periodically closing said circuit when 20 said trunk line is in use, and means controlled by the operation of said switch to operate said meter.

5. In a telephone system, a group of trunk lines, means for making said trunk lines 25 busy, a register for recording the number of times all trunks of the group are busy, means responsive when all trunks are busy for operating said register, and means for recording the cumulative time during which said 30 all trunk busy condition exists.

6. In a telephone system, a group of trunk lines for use in establishing talking connections, and means associated therewith responsive to the use of said trunk lines for 35 at all times showing the number of trunks simultaneously in use.

7. In a telephone system, a trunk line, means for making said trunk line busy, an 40 electromagnetically actuated device for registering the total length of time said trunk is in use, and a current supply and associated circuits responsive to the busy condition of said trunk line for operating said registering device as set forth.

45 8. In a telephone system, a trunk line, means for making said trunk line busy, separate means both responsive to the busy condition of said trunk line for making records of the number of times the trunk becomes 50 busy and the cumulative time the busy condition exists, and means also responsive to said busy condition for giving an alarm should the trunk remain busy for an unusually long period.

55 9. In a telephone system, a trunk line, a line switch, means responsive to a calling subscriber removing his receiver for causing said line switch to seize said trunk line and make said trunk line busy, a register for 60 recording the number of incompletely calls, and means responsive to the calling subscriber hanging up his receiver before completing his call for operating said register.

65 10. In a telephone system, a group of trunk lines, means for making said trunk

lines busy, a register associated with each of said trunks for recording the number of times the associated trunk is busy, a second register associated with each of said trunks for recording the cumulative time the associated trunk is busy, a third register for recording the number of times all trunks of the group are busy, a fourth register for recording the cumulative time during which said all trunk busy condition exists, and 70 means responsive to the busy condition of said trunk lines for operating said registers as set forth.

11. In a telephone system, a group of trunk lines, means for making all of said 80 trunk line busy, and means responsive to an all trunk busy condition for recording the cumulative time during which said all trunk busy condition exists.

12. In a telephone system, a trunk line, 85 means for making said trunk line busy, a register, a circuit for said register, and means responsive to the busy condition of said trunk line for intermittently interrupting said circuit to intermittently operate said register 90 to register the total length of time said trunk line is in use.

13. In a telephone system, a trunk line, means for making said trunk line busy, an 95 automatic switch associated with said trunk line, a meter for registering the number of times said trunk line is taken into use, means responsive to the busy condition of said trunk line for operating said switch a plurality of steps, and means for operating said 100 meter only after said switch has taken a predetermined number of steps.

14. In a telephone system, a series circuit including one conductor of a trunk line, a relay and a meter, said relay being operated over said circuit when said trunk line becomes busy, an automatic switch, means controlled by said relay for closing a circuit to cause the operation of said switch, and means controlled by said switch for short 110 circuiting said relay to cause the operation of said meter.

15. In a telephone system, a series circuit including one conductor of a trunk line, a pair of relays and a meter, only one of said 115 relays being operated over said circuit when said trunk line becomes busy, an automatic switch, means controlled by said operated relay for closing a circuit to cause the operation of said switch, means controlled by 120 said switch for short circuiting said operated relay to cause the operation of said other relay and meter, and means controlled by the said other relay for releasing said switch.

16. In a telephone system, a trunk line, apparatus for recording the number of times and the total length of time said trunk line is in use, said apparatus being normally disconnected from said trunk line, and a 130

manually operated device for operatively associating said apparatus with said trunk line at will.

17. In a telephone system, a trunk line, apparatus for recording the number of times and the total length of time said trunk line is in use, said apparatus being normally disconnected from said trunk line, a third conductor of said trunk line, and a key for operatively associating said conductor with said apparatus for recording purposes.

18. In a telephone system, a group of trunk lines, a device for registering the total number of simultaneous calls in said group, a release conductor for each trunk line of said group, and connections extending from said device to each of said conductors for operatively associating said device with all of the trunk lines of said group.

19. In a telephone system, a trunk line, means for making said trunk line busy, a register, means for removing the busy condition from said trunk line, and means operative in case said busy condition exists for less than a predetermined time for operating said register.

20. In a telephone system, a trunk line, means for making said trunk line busy, a

register for recording the number of incomplete calls, means for removing the busy condition from said trunk line, a relay operative responsive to the removal of said busy condition if the same occurs before a predetermined time has elapsed, and contacts on said relay for closing a circuit to operate said register.

21. In a telephone system, a group of trunk lines, a register, a circuit for operating said register, means for closing said circuit when all said trunk lines become busy and means for intermittently and automatically interrupting said circuit thereafter to cause said register to indicate the time during which the all-trunk busy condition exists.

22. In combination, two devices, an automatic progressively movable switch adapted to cause the operation of said devices, respectively, responsive to two successive operations of the switch, and means for automatically changing the speed of the switch after the first operation thereof.

In witness whereof, I hereunto subscribe my name this sixth day of July, A. D., 1922.

MICHAEL SCHWARTZ.
